UNITED STATES PATENT OFFICE

WILLIAM B. GRIFFITH, OF AUDUBON, NEW JERSEY, ASSIGNOR TO STAR SPRINKLER CORPORATION, OF PHILADELPHIA, PENNSYLVANIA, A CORPORATION OF NEW JERSEY

SPRINKLER FIRE EXTINGUISHING SYSTEM

Application filed October 13, 1930. Serial No. 488,241.

My invention relates to improvements in a sprinkler fire extinguishing system, and particularly to sprinkler systems of the wet type having water under pressure within the system for supplying water to the distributing pipes and the sprinkler heads.

The object of my invention is to provide a sprinkler system of the wet type for buildings which are not subjected to freezing temperatures, and provide extensions, or extension pipes, to the system which may be located in portions of the building, or surrounding buildings, which are exposed to freezing temperature, without danger of the extensions freezing, or the system being impaired by freezing; a further object is to provide a main sprinkler system containing water and extensions thereto containing a pressure medium which may be air, or gas, or any well known non-freeze liquid; a still further object is to provide means which may be in the form of a check valve located between the main system and the extension pipe for preventing the water from the main system from entering the extension pipe through the check valve when the sprinkler heads on the extension pipe are closed; a still further object is to provide means for maintaining the pressure medium in the extension pipe under a pressure which is relatively greater than the pressure of the water in the main system whereby the differential pressure is adapted for retaining the check valve in the closed position, thus preventing water entering the extension pipe where it would freeze and also, when the pressure medium is in the form of a non-freeze liquid, the water will be prevented from entering the extension pipe and mixing with the non-freeze liquid and diluting the same sufficiently to make it liable to freeze; a still further object is to provide a pressure responsive device connected with the extension pipe for yieldingly exerting a pressure upon the pressure medium in the extension pipes to compensate for any reduction of pressure due to leakage.

A still further object is to provide an accumulator and a stand pipe connected therewith containing mercury, to form the pressure responsive device which is connected with the extension pipe; a still further object is to provide means for injecting the pressure medium into the extension pipe and subjecting the same under a pressure greater than the pressure upon the water contained

in the main system, which greater pressure acts against the check valve tending to close the same and also acts against the pressure responsive device, so that the latter will maintain the pressure medium under a nearly uniform pressure; and a still further object is to provide a gage for indicating any variation in the pressure in the extension pipe. These together with various other novel features of construction and arrangement of the parts, which will be more fully hereinafter described and claimed constitute my invention.

The drawing represents a vertical sectional view of a building showing a sprinkler system and the novel features embodying my invention.

Referring to the accompanying drawing in which like reference characters refer to like parts, 1 represents a distributing pipe connected with a riser 2, and 3 represents a main valve, forming part of a sprinkler system of the wet type, such as now in general use and well known in the art. The distributor pipe 1 of the sprinkler system is shown located within a room 4 of a building indicated by the vertical wall 5, the floor 6, and the ceiling 7. The room 4 in which the system 1 is located is heated to prevent the water within the system from freezing. The usual sprinkler heads 8 are connected with the distributor pipe of the main system. A check valve 10 is located in the heated room 4, and is connected with the pipe 1 leading from the system.

Said check valve 10 having a clapper 11 connected with an extension pipe 12 forms part of an extension to the main system. Said pipe 12 extends to a portion or room 9 of the building beyond the wall 5, which is subjected to freezing temperature. The extension pipe 12 is provided with pipe connections 13 upon which the sprinkler head 14, of the usual type, are mounted for protecting the building against damage by fire.

A branch pipe 15, is connected with the extension pipe 12 and also with a pipe 16 connected with a pump 18 having an inlet pipe 19, provided with a cup or funnel 20. Suitable valves 21 and 22 are connected in the pipes 16 and 19 at opposite sides of the pump 18, and the pipe 16 is also provided with a shut off valve 23. The extension pipe 12, the pipe connections 13, and the branch pipe 15 are filled with a pressure medium, preferably a non-freeze liquid, which is

poured into the cup 20 and forced by the pump 18 through the branch pipe 15. The check valve 10 is positioned so that the clapper 11 will be maintained in the closed position by the pressure in the extension pipe 12 so that the non-freeze liquid will not pass into the distributor pipe 1 of the system.

An accumulator tank 25 is connected by a pipe 26 with the branch pipe 15, and said tank is also connected at the lower portion thereof with a pipe 27 having suitable fittings 28 and 29 for clamping a gage glass 30 between said fittings. The lower fitting 29 has connected thereto a pipe 32 which in turn is connected with a stand pipe 33, which latter may be extended to any suitable height within the building, or above the building if necessary. The stand pipe 33 is open to the atmosphere through an over-flow fitting or retaining cup 34. The tank 25 is provided with a filling cup 36 through which mercury may be poured for partially filling the tank 25 and the U-shaped connections formed by the gage glass 30, the fitting 29, and the pipes 32 and 33. The cup 36 is closed by a plug 37 after the mercury is inserted.

The pressure medium, in the form of air, or any non-freeze liquid is forced by the pump 18 into the tank 25 above the mercury, thus filling the pipes 12, 13, 15, 16, and 26. By means of the pump 18, the pressure medium is subjected to a pressure which is greater than the pressure upon the water in the sprinkler system including the pipe 1. The pressure applied by the pump 18 forces the mercury into the stand pipe 33, until the line between the mercury and the air or non-freeze liquid is visible within the limits of the glass 30, thus forming a pressure responsive device adapted for maintaining a nearly uniform pressure within the extension pipe 12 due to the weight of the mercury. The greater pressure in the pipe 12 acts against the clapper of the check valve 10 keeping the latter closed against the lower pressure in the pipe 1 of the main sprinkler system, thus preventing the leakage of water from the pipe 1, through the check valve 10.

Suitable pressure gages 40 and 41 are located at opposite sides of the check valve 10 for showing the relative pressures in the extension or pipe 12 and the pipe 1, with which the gages are connected. The gage glass 30 provides means for detecting any reduction in the pressure in the extension pipe 12, as the level of the low side of the mercury column, when under pressure, will be located within the limits of the gage glass 30, whereby the pressure may be observed through the gage glass. When the fire extinguisher system is opened by the opening of a sprinkler head 14, connected with the extension pipe 12, the pressure medium, or non-freeze liquid, will pass from the pipe 12 through the open heads 14, thereby relieving the pressure from

within the pipe 12 and allowing the check valve 10 to open, thus allowing the water from the distributor pipe 1 of the main system to pass through the check valve 10, and the extension pipe 12 to the sprinkler heads 14. The pressure in the branch pipe 15 and the accumulator tank 25 will be relieved or reduced when the sprinkler heads 14 are opened so that the mercury which was forced up the stand pipe 33 will return and be accumulated in the tank 25, which latter is of sufficient capacity to retain all of the mercury.

When the system is operated by the opening of a sprinkler head 8 the pressure medium in the pipe 12 will be prevented from entering the distributing pipe 1 by the closed position of the clapper of the check valve 10, so that there will be no loss of the non-freeze liquid.

Air may be utilized as the pressure medium instead of the non-freeze liquid, which is used in the preferred operation of my invention. The air may be forced into the system by the pump 18 under a sufficient pressure to displace the mercury from the accumulator tank 25, which will cause the air pressure to hold the check valve 10 in the closed position against a lower water pressure in the distributor pipe 1 of the system, thus preventing the water from entering the extension pipe 12 where it would freeze under a low temperature. The weight of the mercury when forced to an elevated position in the stand pipe will compensate for slight losses in air pressure due to leakage in pipes 12 and 15, thus maintaining the air at a higher pressure than that of the water in the distributor pipe 1 of the main system.

My improved sprinkler system provides means for utilizing a sprinkler system of the wet type for buildings having certain portions thereof which are not heated and in which the ordinary wet type system could not be used without freezing.

My invention provides means for preventing the admission of water through the check valve 10 into the extension pipe 12, and it also prevents the dilution of the non-freeze liquid in the extension pipes, which would make it liable to freeze.

Various changes in the construction and arrangement of the parts may be made without departing from my invention.

I claim:

1. A sprinkler system comprising a distributing pipe connected with a wet type sprinkler system containing water under pressure, an extension pipe containing a non-freeze medium, a check valve connected between the distributing pipe and the extension pipe positioned to automatically open toward the extension pipe, said distributing pipe, said valve, and a portion of said extension pipe located in an area not subject to freezing temperatures, a sprinkler head re-

- sponsive to fire conditions connected with the extension pipe, said head and a portion of the extension pipe located in an area subject to freezing temperatures, a branch pipe connected with the extension pipe, a U-shaped pipe having one leg connected with the branch pipe and extending downwardly therefrom, the other leg being open, mercury in both legs of said U-shaped pipe, the open ended 5 leg being of such a height as to establish therein a difference in heights of the columns of mercury sufficient to produce on the check valve a pressure capable of maintaining it seated against pressure of water in the distributing pipe, and means for subjecting the non-freeze medium to pressure connected in communication with the extension pipe at a point above the level of the mercury in said first mentioned leg whereby the pressure upon 10 the non-freeze medium will act against the mercury in the second mentioned leg and against the check valve. 15
2. A sprinkler system comprising a distributing pipe connected with a wet type sprinkler system containing water under pressure, an extension pipe containing a non-freeze medium, a check valve connected between the distributing pipe and the extension pipe positioned to automatically open toward the extension pipe, said distributing pipe, said valve, and a portion of said extension pipe located in an area not subject to freezing temperatures, a sprinkler head responsive to fire conditions connected with the extension pipe, said head and a portion of the extension pipe located in an area subject to freezing temperatures, an accumulator tank connected with the extension pipe, a U-shaped pipe having one leg connected with 20 said tank and extending downwardly therefrom, the other leg being open, mercury in said tank and in both legs of said U-shaped pipe, the open ended leg being of such a height as to establish therein a difference in heights of the columns of mercury sufficient to produce on the check valve a pressure capable of maintaining it seated against pressure of water in the distributing pipe, and a pump connected with the extension pipe above the level of the mercury in the tank for forcing the non-freeze medium into the extension pipe and subjecting the same to a pressure acting against the mercury in the second mentioned leg and against the check valve. 25
3. A sprinkler system comprising a distributing pipe connected with a wet type sprinkler system containing water under pressure, an extension pipe containing a non-freeze medium, a check valve connected between the distributing pipe and the extension pipe positioned to automatically open toward the extension pipe, said distributing pipe, said valve, and a portion of said extension pipe located in an area not subject to freezing temperatures, a sprinkler head responsive to fire conditions connected with the extension pipe, said head and a portion of the extension pipe located in an area subject to freezing temperatures, an accumulator tank connected with the extension pipe, a stand pipe, a gage glass connected between the lower portion of the tank and the lower end of the stand pipe, mercury in said tank, said gage glass and in the stand pipe, said stand pipe having its upper end open, said stand pipe being of such height above the level of the mercury in the tank to establish therein a difference in heights of the columns of mercury sufficient to produce on the check valve a pressure capable of maintaining it seated against pressure of water in the distributing pipe, and a pump connected with the extension pipe above the level of the mercury in said tank for forcing the non-freeze medium into the extension pipe and subjecting the same to a pressure acting against the mercury in the stand pipe and against the check valve for holding the latter closed against the water pressure in the distributing pipe. 30
4. A sprinkler system comprising a distributing pipe connected with a wet type sprinkler system containing water under pressure, an extension pipe containing a non-freeze medium, a check valve connected between the distributing pipe and the extension pipe positioned to automatically open toward the extension pipe, said distributing pipe, said valve, and a portion of said extension pipe located in an area not subject to freezing temperatures, a sprinkler head responsive to fire conditions connected with the extension pipe, said head and a portion of the extension pipe located in an area subject to freezing temperatures, an accumulator tank connected with the extension pipe, a stand pipe, a gage glass connected between the lower portion of the tank and the lower end of the stand pipe, mercury in said tank, said gage glass and in the stand pipe, said stand pipe having its upper end open, said stand pipe being of such height above the level of the mercury in the tank to establish therein a difference in heights of the columns of mercury sufficient to produce on the check valve a pressure capable of maintaining it seated against pressure of water in the distributing pipe, and a pump connected with the extension pipe above the level of the mercury in said tank for forcing the non-freeze medium into the extension pipe and subjecting the same to a pressure acting against the mercury in the stand pipe and against the check valve for holding the latter closed against the water pressure in the distributing pipe. 35
